H. A. LANDWEHR,
MOLD FOR REINFORCED CONCRETE POSTS AND THE LIKE.
APPLICATION FILED SEPT. 3, 1918.

1,299,739.

Patented Apr. 8, 1919.

UNITED STATES PATENT OFFICE.

HENRY A. LANDWEHR, OF LOS ANGELES, CALIFORNIA, ASSIGNOR TO AMERICAN CEMENT PRODUCTS COMPANY, OF LOS ANGELES, CALIFORNIA, A CORPORATION OF CALIFORNIA.

MOLD FOR REINFORCED-CONCRETE POSTS AND THE LIKE.

1,299,739.

Specification of Letters Patent.

Patented Apr. 8, 1919.

Application filed September 3, 1918. Serial No. 252,342.

To all whom it may concern:

Be it known that I, HENRY A. LANDWEHR, a citizen of the United States, residing at Los Angeles, in the county of Los Angeles,

5 State of California, have invented new and useful Improvements in Molds for Reinforced-Concrete Posts and the like, of which the following is a specification.

This invention relates to means for mold-10 ing and forming reinforced concrete posts and the like, and particularly to molds used for forming hollow reinforced concrete posts by the centrifugal process or method; and the invention has particularly to do 15 with the provision of an improved form of mold and improved forms of means for holding reinforcements or other parts which are adapted to be cast into the concrete body which is formed in the mold. One of 20 the particular features of this invention is the provision of means for holding anchor feet in the mold, to which anchor feet the reinforcements of the finished post, or the like, are attached, and which anchor feet 25 become finally the anchors by which the finished post is secured on its permanent base.

This application forms a continuation in part of my application for reinforced con-30 crete posts and method of making same, filed Nov. 17, 1916, Serial No. 131,821.

The invention will be best understood from the following detailed description of a preferred form of mold and of the method 35 of its use; reference being had for this purpose to the accompanying drawings in which I illustrate preferred forms of devices, and in which—

Figure 1 is a longitudinal section showing 40 the mold and a post in process of formation; Fig. 2 is an end view of the apparatus shown in Fig. 1; Fig. 3 is an enlarged detail section taken as indicated by line 3—3 on Fig. 6; Fig. 4 is a transverse section on line 4—4 of Fig. 1; Fig. 5 is a detail elevation taken as indicated by line 5—5 on Fig. 4; Fig. 6 is a detail section on line 6—6 of

Fig. 3; Fig. 7 is an end view of a modified form; and Fig. 8 is a longitudinal section of the end of the form shown in Fig. 7.

The drawings show a post made up of a cementitious body 10 with suitable reinforcements. The cementitious body may be made in any style or character desired and is preferably, by the centrifugal process, made 55 with an interior longitudinal opening 11, extending from end to end of the post. The exterior ornamentation of the post may be as desired; I illustrate a form of post which is being put into extensive use and is being 60 manufactured by the centrifugal process, in the manner I hereinafter explain. The post shown herein has a fluted surface; and I explain a form of mold which is adapted to cast such a surface, or any other surface 65 which has sunk and raised portions, as most ornamented posts have. The post has a base 12, and in this base I embed the foot brackets 13. These foot brackets 13 are arranged with their horizontal parts extending out 70 beyond the edges of the base to afford facility for connection with permanent foundation bolts and with their vertical parts extending upwardly into the cementitious base to connect at 15 with the reinforcing rods 75 16, which are preferably hooked into the foot brackets 13, in the manner shown. These reinforcing rods 16 may be as many as necessary, but are preferably four in number, as are also the foot brackets, and 80 the rods converge first inwardly and upwardly toward each other and then extend to the top of the post in substantially parallel but slightly convergent relation at the top of the post the rods connect, preferably 85 by hooking, as shown at 17, with the bolts 18. The foot brackets 13 and the bolts 18 form end anchors for the reinforcing rods. It is, of course, immaterial how the rods connect with these anchors; and they may be 90 integrally connected, especially in the case of the bolts 18. In the finished post, these bolts 18 are used to hold the cap plate and lamp fixture in place. In the mold these

bolts 18 pass through the mold cap plate 37 and through closure plate 19 which closes a small opening in the cap plate; nuts 20 serving to hold the closure plate in place 5 and to put tension on the reinforcing rods. The four reinforcing rods 16 are laterally connected by cross wires 22 which are also embedded in the concrete around the central openings 11. These wires 22 are twisted 10 around each reinforcing rod 16 and are arranged diagonally transversely; so that the whole reinforcing structure forms substantially a long square reinforcing skeleton with the rods 16 at the four corners. The reinforcing rods and wires being embedded in the concrete, and the rods being connected and more or less stressed between the upper cap and the lower feet of the post, it will be seen that the finished post is efficiently and 15 strongly reinforced. And this is particularly true because of the fact that the concrete itself is very closely and densely formed around the reinforcements, due to the peculiar action of the centrifugal process which throws the concrete to the outside and the water to the inside, making a voidless, non-porous concrete body.

A typical mold has a central exterior metal shell 30 with mold lining 31 of suitable material, such as wood or metal, and head and base shells 32 and 33 with wooden mold linings 34 and 35. These molds may be parted in any desired manner, as on the three parting lines shown at 35 in Figs. 2 and 4. These parting lines are preferably three in number as that system of parting allows the free withdrawal of the mold from the figured surface of the formed concrete and from the hexagonal base 12. 40 Although a larger number of separable parts may be used if necessary, I find three to be sufficient for most designs. Brief inspection of Fig. 4 will show that the three separable parts will "draw" off the molded concrete. The parts of the mold body may be held together by means as shown at 60; embodying bolt lugs 61 attached in opposing relation to the edges of the parts of shell 31, bolts 62 passing through these lugs; 45 wedges 63 through the bolts, and nuts 64 on the bolts. The bolts may be quickly released by removing the wedges and the nuts may be slightly loosened to loosen the wedges. A cap plate 37 is provided for the 50 mold, this cap plate being secured to the head shell 32 by any suitable fastening means, as by wedges 38. A base plate 39 is likewise provided and similarly secured to the base shell 33 by means of wedges 40. 55 This base plate 39 carries a suitably shaped core 41 for forming the hollow interior 42 of the base of the post. During formation, the foot brackets 13 are held in place by being placed against the base plate 39 within

metal boxes 43. Cap screws or other suitable fastening means 43^a pass through apertures 44 in the base plate and through the apertures 45 in the foot brackets and then screw into the boxes 43 at 46; thus holding the foot brackets 13 rigidly to the base plate, and holding the boxes 43 in place. These boxes are open on their inner ends to receive the foot brackets, and are preferably open on their bottoms so that the foot brackets bear directly against the bottom plate 39, and may be closed at their outer ends. The boxes reach the outer surface of the mold and are removable outwardly when the mold is to be taken off the formed post and when the bolts 43 are removed. The removal of these boxes leaves a clear opening around the projecting parts of brackets 13 sufficient to allow the separation of the mold parts on the parting lines, without the fact in the openings and without any danger of knocking the feet loose in the concrete. The relation of the bracket to the opening may be best seen from Fig. 6 where the opening into which the box fits is designated by numeral 43^b.

The lower ends of the reinforcements having been secured, the upper ends of the reinforcements are then secured by the bolts 18 being passed through the cap plate 37 and closure plate 19 of the mold and the nuts 20 being screwed down upon the plate to draw the reinforcing rods 16 tightly into their proper positions, and to properly stretch the reinforcing rods. The tendency of the reinforcing rods to straighten out and to move apart is resisted by the transverse tie wires 22. The reinforcements are held tightly stretched in a position centering about the longitudinal center of the mold; so that, during the subsequent rotation, there is no tendency of the reinforcements to be displaced from their proper position.

The mold having been assembled, and the reinforcements put in place, as described, the plastic mixture is next placed in the 114 mold. This mixture may have a superfluity of water; and the volume of the mixture and the proportion of water are ascertained by experience and gaged accordingly; so that, when the water is separated from the concrete by the centrifugal action, the resulting solidified body of concrete will leave a central longitudinal opening. The mold having been filled with the fluid concrete, the base plate is closed by its cap 50; the mold is placed in its horizontal position and is placed in the revolving machine, where it is revolved about its central axis at a suitable speed for the required time period to cause the concrete to solidify in the form 115 illustrated. After the concrete has set it may be removed from the mold and subjected to any treatment desired.

A feature of the invention lies in the mold construction, etc. that allows free and ready removal of the mold from the finished molded article. The multiple part mold is 5 one means to accomplish this desired end. Then the removable boxes allow the mold parts to be removed without striking, loosening or displacing the anchor feet. And although this construction is useful even 10 where the number of mold parts and the number of feet is the same, it is particularly useful where the number of mold parts and of feet are not the same and where there must be a considerable space made for free 15 removal of the mold parts from the feet.

It will be seen that a further feature of this arrangement lies in the fact that the reinforcements are, during formation, extended and stretched between the cap plate 20 and the base plate of the mold, holding the reinforcements rigidly and tightly in proper position and at the same time tending to draw the mold ends toward each other. This feature is the result of the 25 mechanical arrangement by which the anchoring means at the top and bottom of the post are secured directly to the cap and base plates of the mold.

In Figs. 7 and 8, I show modified forms 30 of device for accomplishing the same end as hereinbefore described. I show base bars 13^b through which the bolts 18^a extend, these bolts also extending through the base plate 39 of the mold. These base bars 13^b 35 are substantially equivalent to the foot brackets 13, except in the manner of connection of the reinforcing rods 16 with them. The reinforcing rods hook nut bolts 18^a.

40 Having described a preferred form of my invention, I claim:

1. In combination, a column mold adapted to receive cementitious material, comprising a mold body and a detachable end closure 45 plate, and an outwardly removable anchor holding box in and extending through the mold wall and detachably secured to the end closure plate, said box having an open end 50 interiorly of the mold to receive and hold a reinforcement anchor which projects into the interior of the mold.

2. In combination, a column mold adapted to receive cementitious material, comprising a mold body and a detachable end closure 55 plate, and an outwardly removable anchor holding box in and extending through the mold wall and detachably secured to the end closure plate, said box having an open end 60 interiorly of the mold to receive and hold a reinforcement anchor which projects into the interior of the mold, and a bolt passing through the end closure plate and into the box and adapted to pass through the reinforcement anchor.

3. In combination, a column mold adapted 65 to receive cementitious material, comprising a mold body and a detachable end closure plate, and an outwardly removable anchor holding box in and extending through the mold wall and detachably secured to the 70 end closure plate, said box having an open end interiorly of the mold to receive and hold a reinforcement anchor which projects into the interior of the mold, the box being open on its face next the end closure plate 75 so that the reinforcement anchor held therein may bear directly against the end plate.

4. In a separable column mold, a mold body comprising a plurality of separable parts, the wall of a part having a box receiving aperture extending to the exterior surface of the wall so that the box may be removed outwardly, a reinforcement anchor holding box in said aperture, said box having an inner open end to hold an anchor 80 which projects into the mold interior from the inner end of the box opposite the outer end toward which the box is moved for removal, and means for holding the box and the anchor in place. 90

5. In a separable column mold, a mold body comprising a plurality of separable parts, the wall of a part having a box receiving aperture extending to the exterior surface of the wall so that the box may be removed outwardly, a reinforcement anchor holding box in said aperture, said box having an inner open end to hold an anchor 95 which projects into the mold interior, and a single bolt passing through a part of the 100 mold and the anchor and into the box to hold the box and anchor in place.

6. In a column mold for cementitious or plastic material, a mold body divided into a plurality of separable parts, the walls of 105 the parts having box receiving apertures extending from the interior to the exterior surface so that boxes in said apertures may be removed outwardly, and reinforcement holding boxes in said apertures with open 110 inner ends to hold a reinforcement which projects into the mold interior.

7. In a column mold for cementitious or plastic material, a mold body divided into a plurality of separable parts, the walls of the 115 parts having box receiving apertures extending from the interior to the exterior surface so that boxes in said apertures may be removed outwardly, and reinforcement holding boxes in said apertures with open inner ends to hold a reinforcement which projects into the 120 mold interior, the number of said separable mold parts and the number of said box receiving apertures being unequal.

8. In a column mold for cementitious or 125 plastic material, a mold body with a wall having an aperture therein extending from its interior surface to its exterior surface, and a

reinforcement holding box in said aperture,
said box being hollow and open at its inner
end at the inner wall surface to receive a
reinforcement which projects into the mold,
5 and the box being outwardly endwise re-
movable off the reinforcement and out of the
aperture.

In witness that I claim the foregoing I
have hereunto subscribed my name this 6th
day of August, 1918.

HENRY A. LANDWEHR.

Witness:

VIRGINIA I. BERNINGER.
